ABSTRACT

A rectangular gate has a top frame member which carries a latch plate at one end and which houses an initially stressed torsion bar spring at the other end. When suitable vehicle thrust is applied to the gate, it yields along the bottom while the top frame member turns in place, thereby storing spring energy and upending the latch plate until it releases the gate. Propelled by the spring stored energy, the released gate then swings about a vertical axis to its open position where it is automatically latched open for a time interval before returning to its closed position by gravity.

VEHICLE OPENED GATE

FIELD OF THE INVENTION

The present invention relates to gates such as are opened and closed when vehicles enter and leave livestock enclosures, and more particularly to gates which by application of vehicle thrust can be unlatched and set in motion so as to automatically swing free of the vehicle to an open position.

PRIOR ART

Bumper actuated gates came into use when front bumpers of automobiles were more rugged, more resilient and farther in front of the auto body shell than in today's fine cars, and when gates were not required to be wide enough to accommodate modern farm equipment. Most bumper gates previously developed were designed for past conditions rather than present or future requirements.

Many hinged gates formerly were constructed of boards and are now similarly constructed of structurally formed sheet metal strips riveted together. Susceptibility to wind pressure renders such gates unsuitable for free swinging bumper actuated gates. Such prior gates also have poor torsional properties. Other conventional gates tend to be rather heavy and are made even heavier when used as bumper gates, thus carrying additional parts and requiring added strength. After a period of service, the weight and leverage of such gates tends to upset the desired axis of rotation.

The weight of a gate is also a burden on a spring provided to absorb the thrust of a vehicle and to transmit energy to propel the gate open. But weight distribution is even more important than weight itself, because the inertial resistance of mass to rotation of a gate about its axis at a given rate is proportional to the square of the distance of the mass from that axis.

The present gate uses a somewhat similar torsion spring mechanism as is disclosed in applicant's copending patent application Ser. No. 751,530, filed Aug. 9, 1968. There is, however, a difference in the construction, location and application of the present torsion spring mechanism. In the present gate, the torsion spring mechanism and vehicle contacting parts are near the axial end of the gate where their weight has less leverage on the gate's support, where the inertial burden upon the spring is least, and where the stress generated in the gate frame by bumper thrust and spring torque is transmitted most directly to the gate's axis. Additionally, waste of energy through conventional devices for dampening door closing movements is superseded in the present gate by automatic latching of the gate in the open position for a time interval before a free swinging closing movement begins.

SUMMARY OF THE INVENTION

In accordance with the present invention, a tubular longitudinal top frame member forms the base of a near right triangle in which a vertical axle is the altitude and a guy is the hypotenuse. The entire triangle with carried parts is swingable between closed and open gate positions with the turning of the vertical axle. The longitudinal frame member is pivotal along a horizontal axis defined at the axle end by a largely housed initially stiff torsion spring mechanism which is connected with the vertical axle by a horizontal cross pin. Pendant from the longitudinal frame member at its ends are integral arms between which barbed wires are strung to provide a livestock barrier. A third arm is pendant near the axle end of the longitudinal frame member and carries vehicle contact members to which vehicle thrust is applied to open the gate. The latched gate does not yield to vehicle thrust until an initial stress of the torsion spring is overcome, after which the bottom of the gate yields and the top frame member turns in place. The turning stores energy in the spring and upedges a latch plate at the other end of the gate until the latch plate escapes from a keeper, whereupon the spring reverses the turning with sufficient vigor to fling the gate away from the vehicle and to its open position, wherein the gate is automatically latched open for a time interval before returning to its latched closed position by gravity.

The present gate has light thin walled tubular frame members at the top and ends where livestock are not likely to collide with them. A slight bowing of the frame normally tenses the wires. The amount of additional bowing when wires are engaged is limited by safety stops while the gate remains closed.

DRAWINGS

- 10 For a more complete understanding of the present invention and for further objects and advantages thereof, reference is now made to the following description taken in conjunction with the accompanying drawings, in which:
 FIG. 1 is a front view of the present gate in its closed position;
 15 FIG. 2 is a diagram showing successive stages in the opening of the gate;
 FIG. 3 is an enlarged fragmentary side view of the pivot axle of the gate, and related parts;
 20 FIG. 4 is a view taken along line 4—4 of FIG. 3;
 FIG. 5 is a detailed fragmentary vertical longitudinal section of the top frame member of my gate and associated parts;
 FIG. 6 is an enlarged plan view of the latch mechanism and guy attachment;
 25 FIG. 7 is a view of the latch keeper and related parts, taken on line 7—7 of FIG. 6;
 FIG. 8 is a side view of the gate actuating arm, bumper bars and tractor wheel contact roller;
 FIG. 9 is a side view of the spring anchor block 48 of the invention;
 30 FIGS. 10a—c are cross sections taken on line 10—10 of FIG. 5 in different operating positions of the tube 13;
 FIGS. 11a—c are cross sections taken on line 11—11 of FIG. 5 in the conditions shown in FIGS. 10a—c;
 35 FIGS. 12a—c are cross sections taken on line 12—12 of FIG. 5 in the operational positions shown in FIGS. 10a—c;
 FIG. 13 is a side view of the mechanism for latching the gate in the open position, with the latch plate being supported in the lower mounted position;
 40 FIG. 14 is an enlarged view taken along line 14—14 of FIG. 13, hence showing the latch plate and dashpot in section;
 FIG. 15 is a view similar to FIG. 14, but showing the latch plate held in the extreme raised position;
 45 FIG. 16 is a plan view of the mechanism shown in FIG. 14; and
 FIG. 17 is a cross section taken on line 17—17 of FIG. 14.

DESCRIPTION OF THE PREFERRED EMBODIMENT

50 Referring now to the drawings, the numeral 1 refers to the stationary frame which carries the pivoted axle 2 (FIGS. 1 and 3) in an upright position between a flat upper bracket 3 and a U-shaped lower bracket 4 of the frame. The axle is connected to brackets 3 and 4 by means of aligned pivot pins 5 and 6, respectively.

55 The axle 2 is comprised of three parts including a hollow shaft 7, a top plate 8 having an upturned extension 9, and a rectangular loop 10 (FIGS. 3 and 4). The top of loop 10 is perpendicular to the lower end of the hollow shaft to which it is joined, as by welding. The bottom side of rectangular loop 10 rests on the bracket 4 and is perforated to receive the pivot pin 6 which extends downward through perforations in the upper and lower sections of the bracket 4.

60 The internal width of the loop 10 is equal to the outer diameter of a tube 11 which is held in the loop by the bolt 12 which passes through suitable perforations in the opposite sides of the loop 10 and the opposite sides of the tube 11. This connection permits some pivotal adjustment of tube 11 but prevents it from turning on its own axis. Tube 11 extends into tube 13 which is the top frame member of the gate.

65 To frame member 13 are rigidly secured three pendant arms 14, 15 and 16. Arms 14 and 16 are end members of the frame and support barbed wires 17 stretched between them. Arm 15 (FIGS. 1 and 8) may be perforated at 18 and 19 to provide 70 passages for the upper barbed wires. A cross piece 20 is

secured to the lower end of arm 15 perpendicular to the central plane of the gate. Cross piece 20 carries at its ends the upper ends of rubber faced bumper contact bars 21 which are suitably spaced from the barbed wires. The lower ends of the bumper contact bars 21 are connected by a cross bar 22 secured at the central plane of the gate to a hollow shaft 23 which extends from the pendant arm 14 beyond the cross bar 22. Hollow shaft 23 serves as the axle for a tractor wheel contact roller 24 and an anchor for one end of one of the barbed wires.

The top frame member 13 is of thin walled, large diameter tubing, except at the axial end where a thicker walled section 25 provides extra strength. The pendant arm 14 is connected to this thicker walled section. The pendant arm 16, which is of thin walled tubing, is secured to a plate 26 (FIGS. 5 and 6), which is also secured to the end of tubular frame member 13. Plate 26 is sandwiched diagonally between the two thin walled tubular members, and joined to each, as by welding. The upper end of plate 26 is formed to provide two aligned hinge bearing sections 27, the sections having a space between them which is occupied loosely by the end loop 28 of the guy 29. Loop 28 is secured in place by a pin 30 extending through the bearing sections. Outward of the bearing sections, pin 30 further provides pivotal support for the suitably formed spaced ends 31 of the latch plate 32.

The upper end of the guy 29 is enlarged and threaded and passes through a perforation in top plate extension 9 of the axle 2. The guy 29 is held by a nut 33 which can be manipulated to adjust the height of the latch plate carrying end of the gate.

When the gate is in its latched closed position, the latch plate 32 rests flat on the bottom of a recess 34 (FIGS. 5, 6 and 7) of the latch keeper 35 which is secured to the post 36 as by bolting. On the underside of the latch plate 32 is a loop bracket 37 into which the upper end of a strap spring 38 is hooked. The lower end of the strap spring 38 is attached to a formed hook at the lower end of a rod 39 which is secured to the adjacent side of the frame member 16. The upper end of rod 39 is bent outward from the frame member to a position underneath the latch plate 32 near the loop bracket 37 to support the latch plate when it is not supported by the latch keeper 35.

The latch keeper has towards each end a camming section 40 for lifting the latch plate as the gate closes, and also has a plate lowering section 41 between the lifting section and the recess so that the latch plate 32 will enter the region of the recess with a downward rather than an upward movement, thus insuring against the latch plate 32 leaping over the recess when the gate swings fast. Other means for insuring entrapment of the latch plate into the recess are the widening of the recess beyond the width of the latch plate and the tension of the strap spring 38. When the gate is in its closed position the tension of the spring 38 supports a fraction of the weight of the outer end of the gate. When the top frame member of the gate is turned on its axis, the latch plate is tilted as shown by the dotted position 32' (FIG. 7) so that pressure of the latch plate in the direction of the lifted edge will cause the gate to unlatch, which is accomplished by the latch plate riding out of the recess. The loop 28 is held loose enough to adjust to the turning of tube 13.

A cross wall 42 (FIG. 5) is defined in the tubular top frame member 13 where the pendant arm 15 is secured, reinforcing the top frame member at this point of stress. The thick walled section 25 at the axial end of frame member 13 has a working fit around the outer end portion of tube 11. To save material, the intermediate portion of tube 11 is of reduced diameter and has a thinner wall. This intermediate portion extends to a thick end wall 43, the outer diameter of which has a working fit in the interior of tubular member 13. This end wall has a central opening to provide clearance for a torsion bar spring 44.

Torsion bar spring 44 has enlarged square end portions and an intermediate portion of uniform round cross section. The square end portions are mounted in close fitting square chan-

nels 45 and 46 in spring anchor blocks 47 and 48, respectively, so that the spring bar 44 is centered in both blocks. Anchor block 47 has a circular periphery which has a working contact with the interior of the larger diameter portion of tube 11.

Anchor block 48 occupies the space between the cross wall 42 and the end wall 43, and has an outer diameter with a working fit inside the tubular frame member 13 adjacent the cross wall 42.

A bolt 49 passes crosswise through the axial center of anchor block 47 and passes through the walls of tubes 11 and 13 on both sides of the anchor block. A close fitting perforation is provided for the bolt through the tubes outward of the anchor block are circumferentially elongated as shown in FIGS. 10a-c. The spring bar 44 is slightly shorter than the distance from the bolt 49 to the cross wall 42, so that end thrust generated by the guy 29 against tubular frame member 13 will be transmitted by the cross wall 42 of tube 13, through the anchor block 48 to the end wall 43 of tube 11, and thence to the bolt 12 and axle 2.

Spring anchor block 48 has on each side two opposite recessed quadrants. The two recessed quadrants on the side facing and adjacent to the end wall are shown in FIGS. 5, 9 and 11a-c. As indicated in FIG. 9, each of the recessed quadrants on this side of the anchor block extends from a radial shoulder 50 to another radial shoulder 51, and outward from an annular shoulder 52. Similarly, the two recesses on the opposite side of the anchor block 48, which side faces and is adjacent to the cross wall 42, extend between radial shoulders 53 and 54 and outward from annular shoulder 55, as shown in FIGS. 5 and 12a-c.

As shown in FIGS. 11a-c, the two recesses facing the end wall 43 receive projections 56, which are integral with the end wall and correspond to the recesses receiving them. However, the projections are angularly shorter than the recessed quadrants, thus permitting some relative rotary movement between the end wall 43 and the spring anchor block 48.

As shown in FIGS. 12a-c, the two recesses of the spring anchor block 48 facing the cross wall 42 receive projections 57 which are integral with the cross wall and cylindrical wall of the tubular frame member 13 and correspond to the recesses receiving them, except that the projections are angularly shorter than the recessed quadrants, thus permitting some relative rotary movement between the cross wall 42 and the spring anchor block 48.

Since the end wall 43 is integral with the tube 11 which is prevented from turning on its axis by the bolt 12, the projections 56 thereon maintain a fixed position and limit the counterclockwise movement of the spring anchor block 48. Since the projections 57 of cross wall 42 are integral with the tubular top frame member 13 of the gate, they move with tube 13 when tube 13 is turned.

When the gate is in its normal closed position free from external force, the barbed wire barrier defines a vertical plane with the top frame member of the gate 13 and the three pendant arms 14, 15 and 16. In this position, the latch plate makes a flat contact with the bottom of the recess of the latch keeper, the adjacent openings through tubes 11 and 13 for the bolt 49 register, and the torsion spring bar is torsionally stressed, or twisted, between the two spring anchor blocks. By comparing the horizontal and vertical sides of the rectangular spring channel 45 in FIG. 10a with the clockwise turned spring channel 46 in FIG. 11a, the degree of twisting in the spring can be noted, for the sides of the two ends of this spring are in common planes when the spring is not stressed. The torque produced by this degree of twisting urges the spring anchor block 47 clockwise and holds the bolt 49 against shoulders 60, of the top and bottom walls of tube 11. Since tube 11 cannot turn on its axis, the bolt is now at its extreme clockwise position.

While the twist in the spring is putting clockwise torque on spring anchor block 47, it is putting counterclockwise torque on anchor block 48 (FIGS. 11a and 12a). The counter-

clockwise rotation of block 48 is limited by contact of its radial shoulders 50 with radial shoulders 58 of the projections 56 (FIG. 11a), the position of which is fixed because tube 11 cannot turn on its axis. At the same time, the radial shoulders 53 on the opposite side of anchor block 48 are forced against radial shoulders 61 of projections 57 of the cross wall 42. Thus, the spring pressure through radial shoulders 53 resists clockwise rotation of the top frame member 13 of the gate, and the spring pressure acting through bolt 49 against the shoulders 59 of the wall of the thick walled portion 25 of frame member 13 resists the counterclockwise rotation of the top frame member of the gate.

When bumper thrust forces the tubular top frame member 13 to turn clockwise enough to unlatch the gate, the shoulders 59 of tube 13 are withdrawn from bolt 49 as shown in FIG. 10b but the bolt is held stationary by the shoulders 60 of the non-turnable tube 11. This holds the spring anchor block 47 and the therein confined end of the torsion bar spring from turning clockwise. Instead, the clockwise advance of projections 57 with the tubular frame member 13 has moved the spring anchor block 48 clockwise as shown in FIG. 12b, thereby increasing the angular disparity between the two ends of the spring and therefore increasing the torque of the spring. The clockwise rotation of spring anchor block 48 has withdrawn the radial shoulders 50 of the end wall facing side of anchor block 48 from the radial shoulders 58, as shown in FIG. 11b.

When bumper thrust has forced the tubular top frame member 13 counterclockwise (FIG. 10c) to the amount required to unlatch the gate, the shoulders 59 of tube 13 have rotated the bolt 49 counterclockwise as seen in FIG. 10c, thereby rotating the spring anchor block 47 and the therein gripped end of the torsion bar spring.

While the spring anchor block 47 is turned counterclockwise as shown in FIG. 10c, the spring anchor block 48 remains at its position of contact with the stationary projections 56 as shown in FIG. 11c, and the rotation of tube 13 has moved the shoulders 61 of the projections 57 away from the radial shoulders 53 of spring anchor block 48, as shown in FIG. 12c.

Generally livestock will avoid barbed wire barriers. Should an animal seek to force its way through the barbed wire barrier of this gate, the animal would ordinarily make the attempt near the longitudinal middle of the gate, away from posts and thicker parts. Pressure against the wire at this location will result in an increase in the tension of the wire considerably greater than the perpendicular pressure against the wire. Such tension in the lower wires of the gate will cause top frame member 13 to bow upward and the bottoms of end members 14 and 16 of the frame to be drawn toward each other. To prevent overstraining of the frame, safety stop lugs 62 and 63 are provided at the bottom of pendant arms 14 and 16, respectively. The end portions of these lugs are turned at right angles to interlock with similar lugs 64 and 65 projecting from the frame 1 and post 36, respectively, thereby limiting the inward movement of the pendant arms 14 and 16 when the gate is in its closed livestock confining position. Owing to the initial stress of the torsion bar spring, the force of an animal against the wire barrier may not open the gate even though the wire is damaged. By placing the lug 65 beneath the lug 63 and providing a post carried guard 66 above lug 63, the distal end of the gate is protected against abnormal vertical displacement in its closed position.

To open the gate, drivers of tractors having front wheels in the lead will contact the roller 24 with the front wheel that is nearest the axial end of the gate. To open the gate with an automobile or truck, about one fourth of the bumper will be on the axial side of the bumper contact bar of the gate when thrust is applied slowly thereby causing the bottom of the gate to yield while the top frame member 13 of the gate turns in place. Owing to the small amount of mass along the bottom of the gate, there is little inertial shock generated on contact. The turning of frame member 13 increases the amount of twist between the ends of the torsion bar spring, thereby storing

energy. It also tilts the latch plate until its lifted side escapes from the recess of the latch keeper.

In FIG. 2, the line 67 represents the position of the top of the gate, and the line 68 indicates the position of the bottom of the gate at the time the latch plate becomes released. The left end of line 67 represents the axle end of the gate. The arrow 69 indicates the location of the bumper contact bar relative to the two ends of the gate. At the time when the latch plate is released, the point of contact between the bumper and the bumper contact bar is approximately underneath the top of the gate. Upon release of the latch plate from its keeper, the torsion bar spring reverses the turning of the top of the gate. Presuming there is no further movement of the vehicle against the bumper contact bar, the reversed turning of the top of the gate will move the gate to the dotted line 70 by the time the gate has been restored to its vertical position, thereby terminating the impulse of the torsion bar spring. However, by this time the gate has attained sufficient velocity to continue its swing to its open position without further vehicle thrust.

20 The axle 2 is tilted towards the post 36 so that the gate will swing from its open position back to its closed position by gravity with sufficient momentum to cam the latch plate into the recess of the latch keeper.

25 To maintain the posture of the gate frame 1, this frame may be pivoted at a base 71 and adjustable at an anchor bolt 72.

The bolt 12 may be designed to shear off under excessive

bumper thrust. Shielding may be provided to keep rain and

other water from entering the torsion spring mechanism.

30 The invention further comprises structure to latch the gate in the open position for a time interval to permit the vehicle to drive past the gate before the closing movement of the gate begins. This is accomplished by the latch mechanism on the swinging part of the gate in conjunction with cooperating parts mounted on a post 73 of hollow square section (FIGS. 13 to 17). This tubular post is closed at the top to prevent internal corrosion and is supported by a brace 74 to maintain its proper distance relative to the path described by the latch plate when the gate swing open.

40 At the upper end portion of post 73 is a carriage 75 comprising a basal post enclosing girdle 76, an upper post enclosing girdle 77 and two upright parallel flat bars 78 and 79 incorporated into and connecting the two girdles. The bars 78 and 79 extend sideways beyond the side of the post and extend at two locations vertically beyond the upper girdle, where these two bars have aligned holes which serve as bearings for the horizontal pivot shaft 80. An integral arm 81 extends upward from one end of shaft 80. The arm 81, in turn, has a laterally extending integral latch plate lifting arm 82 which is longitudinal to the swing path of the outer end portion of the latch plate 32.

45 Any suitable dash pot 83 is mounted between a pivot pin 84 on the arm 82 and a cross pin 85 connecting the bifurcated lower end 86 of the dashpot with an extension 87 of the basal girdle of the carriage 75.

50 A nut 88 is fixedly secured to the basal girdle and the extension 87. Through this nut is threaded a bolt 89 which is supported by a bracket 90 of the post 73. By manipulation of the bolt, the carriage can be adjusted vertically to suit the height of the latch plate of the gate.

55 The outer end of the latch plate lifting arm 82 cams the latch plate 32 upward as the latch plate advances with the opening swing of the gate towards the upright arm 81. The opening swing of the gate is then stopped as the latch plate strikes arm 81 and pivots it so the projection 91 on the side of arm 81 makes contact with the backstop 92 which is formed at the upper end of upright bar 78. The angular movement forced upon upright 81 by the momentum of the gate is accompanied by a similar angular movement of the integral latch plate lifting arm 82. However, the angular disposition of the latch plate 32, as seen in FIGS. 14 and 15, does not change since it is determined by the inclination of the gate in its open position, which in turn, is determined by the inclination of the axle 2 (FIG. 1). Hence, the pivoting forced upon arm 81 by

the thrust of the advanced edge of the latch plate causes the arm 82 to elevate the latch plate by contact along the trailing portion of the latch plate. A recess defined in the top of arm 82 by the shoulder 93 and surface 94, receives the trailing portion of the latch plate, as shown in FIG. 15, thus latching the gate in its open position. A lug 95 extends over the edge of the latch plate from the top of arm 81 to further confine the latch plate to its latched position as the post 73 vibrates from the impact of the gate.

To minimize trouble from icing, arm 82 is narrow at the top and is stiffened by a flange 96 at the bottom. The flange 96 extends from the upright 81 to the pivot pin 84, but is omitted beyond this pin. The upper surface of the arm 82 is contoured to receive the pressure of the latch plate at the upper end of surface 94 so that the pressure of the latch plate, which is due to the tension of the strap spring 38, will be transmitted to a large extent to the dashpot. The dashpot delays the return of the latch plate from the elevated latched position shown in FIG. 15 to the lowered unlatched position shown in FIG. 14. When the latter position is reached, gravitational force acting on the gate by virtue of the inclined axle 2 then overcomes the friction between the latch plate and the arm 82 and swings the gate back to its closed position.

As the present gate opens towards either direction from its closed position, it is necessary to employ a post 73 and the mechanism thereon at the two open positions of the gate, the mechanism being similar in the two positions, except that there is a right handed and left handed relationship.

The dashpot here presented is comprised of a hydraulic chamber 97 made by combining two shells 98 and 99 with a band 100, including a perforated plate 101 secured between the two shells. The rod 102 is pivotally secured at its upper end to the pin 84 and extends downward through an opening at the top of the hydraulic chamber and through a central opening in plate 101. The lower end of this rod rests at the bottom of the hydraulic chamber when the arm 82 is in its lowest position, as shown in FIG. 14. A hood 103 is fixedly secured to the rod above the hydraulic chamber to protect the entrance to the hydraulic chamber from dirt and rain.

A valve seat 104 is fixedly secured in the hydraulic chamber at such distance above the plate 101 as may be desired for the valve 105 and valve spring 106. The valve is designed to cover the large central opening in the valve seat. The valve has an elongated tubular shank 107 about the rod and may be fitted loosely enough about the rod to bypass fluid, or else a special bypass 108 may be provided through the valve seat.

As previously explained, the gate's opening movement ends with a very quick shift of arm 82 from its lower position shown in FIG. 14 to its higher position shown in FIG. 15, thereby effecting an equally quick raising of the rod 102 in the hydraulic chamber which is filled with a hydraulic fluid well above the valve seat. During this lifting of the rod, the fluid above the valve overcomes the pressure of the valve spring and flows downward past the valve and through the perforations in plate 101 to occupy the space vacated by the rod. The valve spring then returns the valve to its closed position against the valve seat and the rod begins its downward thrust due to the tension of the strap spring 38 on the latch plate 32. This downward thrust is transmitted to a large part to the rod 102. Owing to the limited rate of flow of displaced fluid upward through the space between the rod and valve shank 107, or alternately, through a special by-pass 108, the gate remains latched for a time interval, but is eventually released to commence its swing to its closed position. A strap spring may be hooked at the eyelet 109 to apply a downward pull to arm 82 if it is desired to shorten the time interval the gate remains latched in the open position, or in gates using a rigid latch plate.

Although the present invention has been disclosed with respect to a specific embodiment thereof, it will be understood that various changes and modifications will be suggested to one skilled in the art, and it is intended to encompass such changes and modifications as fall within the scope of the appended claims.

What is claimed is:

1. An automatic gate comprising:
a generally rectangular gate unit,
first supporting means for pivotally supporting said rectangular unit at an upper level along longitudinally spaced intervals defining a longitudinal pivot axis,

means for pivotally supporting said first supporting means and the thereon supported rectangular unit at vertically spaced intervals along a vertical pivot axis adjacent one end of the rectangular unit for pivotal movement of the gate from its closed position in either direction to an open position,

a latch member so constructed and so mounted on said rectangular unit that the latch member's posture will retain the gate in the closed position when the rectangular unit is in its normal vertical posture and will release the gate from its closed position when the rectangular unit is pivoted on said longitudinal pivot axis to certain clockwise and counterclockwise tilted postures,

means for receiving the thrust of a motor vehicle along the lower part of said rectangular unit for forcibly pivoting said rectangular unit about said longitudinal pivot axis to said latch releasing postures, and

resilient means for storing energy when said rectangular unit is pivoted about said longitudinal pivot axis by a vehicle to an unlatching tilted posture and for returning said rectangular unit to its vertical posture after latch release with sufficient vigor to fling the gate away from the thrust applying vehicle and to the open position.

2. An automatic gate comprising:
a generally vertically disposed rectangular gate unit,
first supporting means for pivotally supporting said rectangular unit at an upper level along longitudinally spaced intervals defining a longitudinal pivot axis about which the rectangular unit can be pivoted,

means for pivotally supporting said first supporting means and the thereon supported rectangular unit at vertically spaced intervals along a vertical pivot axis adjacent one end of the rectangular unit for pivotal movement of the gate from its closed position in either direction to an open position,

latch means for holding the gate closed at the opposite end from said vertical pivot axis until said rectangular unit is pivoted to a certain angular position about said longitudinal axis,

means for receiving the thrust of a vehicle along the lower level of the rectangular unit, and

resilient means along said longitudinal pivot axis for storing energy when said rectangular unit is pivoted about said longitudinal pivot axis by a vehicle to unlatch said gate and for applying the stored energy to fling the gate away from the vehicle and to an open position, once the gate has been unlatched.

3. In a vehicle actuated gate, the combination comprising:
a gate,

means for mounting said gate for pivotal movement about a longitudinal axis from a normal vertical posture in either direction to tilted postures,

vertical axial means for mounting said gate for pivotal movement about a vertical axis from a closed position in either direction to an open position,

spring means along said longitudinal axis for communicating torque for resisting pivotal movement of said gate about said longitudinal axis and for forcefully returning said gate from a tilted posture to the normal vertical posture, said spring means communicating torsional forces to said vertical axial means,

structure mounted on said gate for receiving the thrust of a vehicle for pivoting said gate on said longitudinal axis, and

latch means for retaining said gate in its closed position until said gate is pivoted to certain tilted postures, then to release said gate from latch retention, whereupon said spring means returns said gate to its vertical posture with such vigor as to fling the gate from said thrust applying vehicle to an open position.

4. In an automatic gate, the combination comprising:
an axle pivotally mounted along a generally vertical pivot line,
a second axle pivotally joined to said vertical axle for pivotal movement in a vertical plane,
a generally vertical livestock barring unit pivotally mounted at one upper end on said second axle member along a longitudinal pivot axis,
a guy supporting the opposite end of said livestock barring unit from a higher elevation,
latch means for holding the gate closed until said livestock barring unit is pivoted to a certain angular position about said longitudinal axis,
vehicle contacting means along the lower part of said livestock barring unit such that a vehicle may force said unit to pivot to the latch releasing angular position, and
spring means for storing energy when said livestock barring unit is pivoted to the latch releasing angle and thereupon applying said stored energy to swing the gate away from said vehicle and to an open position.
5. The automatic gate of claim 4 and further comprising:
means for restraining the guy supported end of the livestock barring unit from vertical displacement while in the normal closed position.
6. A vehicle opened gate mounted at one end to swing between closed and open positions about a vertical pivot axis and constructed to tilt about an upper longitudinal axis, comprising:
latch means for holding the gate closed at said upper longitudinal axis and for releasing the gate from the closed position when the gate has been tilted to a certain angular posture by the thrust of a vehicle,
an elongated torsional spring mounted along said upper longitudinal pivot axis,
structure to hold the spring initially stressed and thereby hold said gate in a vertical posture until the initial stress is overcome by the thrust of a vehicle at the lower part of the gate, and to torsionally stress said spring additionally when the gate is being tilted to the latch releasing posture, and
said spring having capacity to store enough energy when so additionally stressed to return said gate to its vertical posture with sufficient vigor after latch release to fling the gate away from the thrust applying vehicle and to its open position.
7. In an automatic gate, the combination comprising:
an upright axle mounted for rotation about an upright pivot axis at one end of the gate,
an inner tubular member extending substantially perpendicularly from a horizontal pivotal connection with said upright axle,
an outer tubular member having one end surrounding and riding pivotally on said inner tubular member,
a guy supporting the other end of said outer tubular member from a higher elevation,
a torsion bar spring concentric in said inner and outer tubular members,
spring twisting means for communicating torque between one end of said spring and each of said tubular members in a clockwise direction,
spring twisting means for communicating torque between the other end of said spring and each of said tubular members in the counterclockwise direction, and
said spring being initially torsionally stressed between the spring twisting means at its two ends whereby the rotation of said outer tubular member in either direction is resisted first by said initial torsional stress and then additionally by additional twisting of said spring.
8. The gate according to claim 7 and further distinguished by said upright axle having a loop at its lower end, and with said inner tubular member extending into said loop and being pivotally connected therewith by means of a cross pin extending through the two sides of said loop and the two sides of said inner tubular member.

9. In an automatic gate mounted to swing in either direction between closed and open positions about a vertical pivot axis, the combination comprising:
a generally vertical and generally rectangular livestock barring unit,
said unit having a frame extending longitudinally along its top and downwardly along its two ends, the longitudinal section along the top being the entire frame connection between the two ends,
wires strung tensioned between the two ends,
means at the lower extremity of each frame end to limit the distance the frame ends can be drawn toward each other at their lower extremities by additional wire tension while the gate is in its closed position,
said means including structure formed and spaced at one of said frame ends to connect the lower extremity of that frame end with an adjacent cooperating stationary object when the frame end is drawn a predetermined amount toward the other frame end while the gate is in its normal closed position.
10. In a vehicle actuated gate, the combination comprising:
a generally vertical and generally rectangular livestock barring unit,
said unit having a frame section longitudinally along its top and vertically along its two ends, the longitudinal section along the top being the entire frame connection between the two ends,
wires strung tensioned between the ends of said frame,
structure for receiving vehicle thrust fixedly joined to and pendant from the longitudinal section of said frame intermediate of the two ends,
support means for said rectangular unit pivotally connected with said longitudinal frame section adjacent to the ends of the livestock barring unit for movement about a longitudinal axis, and
frame means for pivotally supporting said support means at vertically spaced intervals along a vertical pivot axis adjacent to one end of said rectangular unit so the unit can be pivoted from a closed position in either direction to an open position.
11. The gate of claim 10 and further comprising:
means to limit the distance the lower parts of the frame ends can be drawn towards each other by additional wire tension while the gate is in its closed position, and
said means comprising structure at the bottom of each frame end formed and spaced to connect with an adjacent cooperating stationary object when the lower end of the frame is drawn a predetermined amount towards the opposite frame end.
12. A gate mounted at one end for rotation about a vertical axis from a closed position in either direction to an open position, and also mounted for movement at the bottom about an upper longitudinal pivot axis defined at one end by a latch plate for holding the gate in its closed position, and further comprising:
a keeper for said latch plate mounted on a support adjacent said gate,
spring means for urging said latch plate down upon said keeper,
said keeper having a recess for said latch plate less than half as deep as said latch plate is wide for permitting release of said latch plate by upending when the bottom of said gate is pivoted about said longitudinal axis by the thrust of a vehicle, and
resilient means to store energy when the bottom of the gate is pivoted about said longitudinal axis by a vehicle to release said latch plate from said keeper and to fling the gate away from said vehicle and to an open position about said vertical axis when the gate is released by said latch plate.
13. In an automatic gate mounted at one end to swing laterally between closed and open positions and having means urging a closing movement from the open position, latching

means for latching the gate in the open position for a time interval before it begins its closing movement, said latching means comprising:

a latch member mounted on said gate in a generally horizontal position for vertical movement,
a tilting unit carried by a stationary support and having a generally upright arm with a latch blocking portion for engaging and arresting said latch member at the end of the opening movement of said gate,
said tilting unit being pivoted at a level below said latch blocking portion so said upright arm tilts backward from a normal position in response to the thrust of the latch member generated by the momentum of the gate,
said tilting unit having a latch lifting arm extending forward from said upright arm such that when the upright arm is thrust backward the latch lifting arm swings upward from a normal lower position to a raised position and carries said latch member upon itself to a raised position,
means for restraining said latch member from gate closing movement while said lifting arm is in said raised position and for releasing said latch member for such movement when said lifting arm is in its normal lower position,
spring means for returning said lifting arm to its normal lower position, and
a dashpot connecting said tilting unit with said stationary support to retard the lowering of said lifting arm to its normal lower position and thus provide a time interval during which said latch member is restrained and said gate is held open before it begins its closing movement.

14. An automatic gate according to claim 16 and with said

latch lifting arm normally disposed in the swing path of said latch member at an elevation adapted to cam said latch member upon itself when the gate nears its fully open position in its opening movement.

5 15. In a gate mounted at one end for rotation about a vertical pivot axis from a closed position in either direction to an open position,

a longitudinal livestock barrier unit,
means for mounting said barrier unit for pivotal movement at the bottom about an upper longitudinal pivot axis from a normal vertical posture to clockwise and counterclockwise tilted postures,

means for receiving the thrust of a motor vehicle along the lower part of said barrier unit for forcibly pivoting said barrier unit about said longitudinal axis,
a latch member mounted on said barrier unit for retaining the barrier unit in the closed position when the barrier unit is in its normal vertical posture and for releasing the barrier unit from the closed position when the barrier unit is pivoted on said longitudinal pivot axis to predetermined clockwise and counterclockwise tilted postures, and

resilient means for storing energy when said barrier unit is pivoted about said longitudinal pivot axis by a thrust applying vehicle to an unlatching tilted posture and for returning said barrier unit to its vertical posture with sufficient vigor after latch release to fling the gate about said vertical axis away from the thrust applying vehicle and to an open position.

UNITED STATES PATENT OFFICE
CERTIFICATE OF CORRECTION

Patent No. 3,657,842 Dated April 25, 1972

Inventor(s) Felix B. Romberg

It is certified that error appears in the above-identified patent and that said Letters Patent are hereby corrected as shown below:

Col. 4, line 64, "10a" should be --10a--.
Col. 6, line 39, "swing" should be --swings--.
Col. 11, line 30, "16" should be --13--.

Signed and sealed this 31st day of October 1972.

(SEAL)
